US0D1031722S

(12) **United States Design Patent** (10) **Patent No.:** **US D1,031,722 S**
(45) **Date of Patent:** **** Jun. 18, 2024**

(54) **NOTEBOOK COMPUTER**

(71) Applicant: **Acer Incorporated**, New Taipei (TW)

(72) Inventors: **Hsueh-Wei Chung**, New Taipei (TW);
Pao-Ching Huang, New Taipei (TW);
Hung-Chi Chen, New Taipei (TW);
Kai-Teng Cheng, New Taipei (TW)

(73) Assignee: **Acer Incorporated**, New Taipei (TW)

(***) Term: **15 Years**

(21) Appl. No.: **29/736,107**

(22) Filed: **May 27, 2020**

(30) **Foreign Application Priority Data**

Nov. 28, 2019 (TW) 108307271

(57) **CLAIM**

The ornamental design for a notebook computer, as shown and described.

DESCRIPTION

FIG. 1 is a perspective view of a notebook computer showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines illustrate portions of the notebook computer that form no part of the claimed design.

1 Claim, 5 Drawing Sheets
